By H. A. Seymour Attorney

UNITED STATES PATENT OFFICE.

CHARLES ANDERSON, OF SOUTH BEND, INDIANA, ASSIGNOR TO THE SOUTH BEND IRON WORKS, OF SAME PLACE.

PLOW.

SPECIFICATION forming part of Letters Patent No. 348,652, dated September 7, 1886.

Application filed June 11, 1886. Serial No. 204,871. (No model.)

To all whom it may concern:

Be it known that I, CHARLES ANDERSON, of South Bend, in the county of St. Joseph and State of Indiana, have invented certain new and useful Improvements in Plows; and I do hereby declare the following to be a full, clear, and exact description of the invention, such as will enable others skilled in the art to which it appertains to make and use the same.

10 My invention relates to an improvement in plows.

In my applications for Letters Patent entitled "Sulky-Plows," filed on June 5, 1886, and June 7, 1886, Serial No. 204,223 and No. 15 204,434, a plow was described as well adapted for use in combination with a sulky-plow, but it possessed features which were of general application to plows, either hand or wheel, and said features were reserved as the subject-20 matter of the present application.

The object is to provide a plow which shall consist of few parts capable of being combined by the use of few bolts, and so combined that there will be no tendency to work loose, forming a compact, strong, and durable plow for general use.

With these ends in view my invention consists in certain features of construction and combination of parts, as will be hereinafter 25 described, and pointed out in the claims.

In the accompanying drawings, Figure 1 is a view of the plow in perspective. Fig. 2 is an inverted perspective. Fig. 3 is a horizontal section; and Fig. 4 is a detached view of the 35 casting to which the mold-board, landside, point, and standard are attached.

The plow-beam N is of the channel type, and at its rear end, where it forms the plow-standard n, it is formed nearly or quite straight, 40 extending downwardly to the foot of the plow, and then bending forwardly with a sharp turn, as shown at n'.

For securing the mold-board, landside, and point to the standard, a peculiar-shaped casting, O, is provided, as follows: The side o of the casting is shaped to conform to the curve of the mold-board P and furnishes an extended seat for the same. It also extends low enough to form an extended bearing for the 45 plow-point and wing p. The side o' of the

casting extends rearwardly at the same angle with the side o as the landside p' makes with the mold-board and forms an extended seat for the landside. The sides o and o' of the casting are firmly united by a horizontal web, 55 o², a short distance above the foot, and by the increased thickness of metal at the upper end o³. The lower end of the plow-beam N or standard n fits snugly beneath the web o², and a rib, o⁴, at the rear edge of the side o' of the 60 casting, is adapted to fit snugly in the groove in the side of the beam or standard. The beam is locked in its adjustment by means of one or more bolts, Q, (one is sufficient,) which extends transversely through the beam and 65 the side o' of the casting, and by a long bolt, q, which extends upwardly through the foot of the standard n, web o², and re-enforced top o³ of the casting. This latter-named bolt is not, however, absolutely necessary to secure the 70 beam to the plow, but it tends to materially strengthen the attachment and prevent any possible play between beam or standard and plow. The distance of the web o² above the foot of the plow is naturally determined by 75 the depth of the end of the standard n, the object being to allow the latter sufficient room to keep it above the foot-bearing of the plow and yet not reduce its depth enough to weaken it.

The attachment on the end of the plow-beam for applying the draft at different points to the right and left of the beam center consists of a transverse perforated bar, R, projecting farther on the furrow side than on the 85 land side of the beam, to the rear edge of which are secured a pair of rearwardly-extending jaws or branches, r, adapted to embrace the opposite sides of the plow-beam, to which they are secured by bolts r', extending 90 through the jaws or branches and the beam. A strengthening-brace, r², extends from the furrow end of the bar R to the jaw or branch r, near its rear end.

The clevis S consists of an upright perforated bar terminating rearwardly in a pair of jaws, s, which snugly fit the upper and lower sides of the bar R and lip over the front of said bar, as shown at s'. By sliding the clevis along the bar R and locking it in different po- 100

sitions thereon by a draw-bolt, s^2 , the plow may be made to take more or less land as desired, and may be held up to its work in side-hill plowing, where the tendency is to constantly work away from the land.

The plow, when used as a hand-plow, may be provided with one or a pair of handles for guiding it, and they may be attached to the mold-board or to the casting or to the beam or to standard in any well-known or approved manner to suit the size and weight of the plow or the purposes for which it is to be employed.

It is evident that the shape of the casting O may be modified in many respects, and that the plow-beam may be varied from a straight upright at the standard end n , and that other slight changes may be resorted to without departing from the spirit and scope of my invention; hence I do not wish to limit myself strictly to the construction herein set forth; but,

Having fully described my invention, what I claim as new, and desire to secure by Letters Patent, is—

1. In a plow, the combination, with a plow beam and standard, of a casting adapted to form a seat for the several wearing parts of a plow, the said casting having a web located between and integral with the sides of the casting, and a landside-rib forming a seat for the lower end of the standard.

2. In a plow, the combination, with a casting adapted to form a seat for the several wearing parts of the plow, and having a web integral with the sides thereof, and a rib integral with one side thereof, of a plow-standard having a channeled face adapted to be engaged by the rib, and a forwardly-projecting end section adapted to engage the web, substantially as set forth. 35

3. In a plow, the combination, with the plow beam and blade, of a horizontal bar having perforations and provided with rearwardly-extending jaws for securing it to the beam, the said bar being braced at the furrow end 45 by a rigid brace extending from it to the jaw, and a clevis consisting of an upright perforated bar provided with a pair of jaws adapted to rest against the opposite faces of the horizontal bar and be secured to the transverse bar in the desired lateral adjustment, substantially as set forth. 40

In testimony whereof I have signed this specification in the presence of two subscribing witnesses.

CHARLES ANDERSON.
